RECEPTACLE CLOSURE

Georgina F. Jonitz, Washington, D. C.

Application June 7, 1934, Serial No. 729,510

8 Claims. (Cl. 229—47)

The invention relates to improvements in receptacle closures and refers more particularly to closures for cartons of cardboard or similar materials such as are generally used for shipping purposes.

In containers of the character described the disadvantage is often observed that it is impossible to close the container again after it has once been opened and to keep it closed until ready for further use. Particularly if such containers or cartons contain food or food products which may be spoiled by the unrestricted admission of the atmosphere, or which may easily be spilled out of the carton by careless handling thereof, it becomes desirable to provide means for closing the carton.

Various kinds of closing means have been designed to remedy the above-mentioned disadvantages and to improve the untidy appearance which cartons usually assume when once opened. However, all of the known devices are either too expensive in manufacture or too difficult in operation to be of real practical use.

The primary object is to provide a novel closure means or lock whereby the cover or lid of a carton or similar container may be releasably held in closed position after the container has been opened.

A further object of the invention is to provide a closing means for receptacles as described which is of very simple and cheap construction, which is very simple in operation and which may either be sold by itself or readily applied in a container.

My invention has for a still further object the provision of containers of the general character described with novel closure means whereby the cover or lid will be held in closed position during shipment and storing of the goods contained therein and wherein the usual closure means consisting of paper wrapping or the like is strengthened.

The objects of my invention are accomplished by the device described in the following specification and shown in the accompanying drawing in which:

Fig. 1 shows a perspective view of a carton or similar receptacle having my novel closure means applied thereto.

Fig. 2 is a rear view of my device as applied to a carton.

Fig. 3 is a detail sectional view on lines 3—3 of Fig. 1.

Fig. 4 is a similar section through a carton having an inner package for the goods and showing the position of the device during shipment.

Fig. 5 is a front view of my device before being applied to a carton.

Fig. 6 is another front view of my invention with its tapered end bent upwardly.

Fig. 7 is a side view of Fig. 6, and

Fig. 8 is a section similar to the one shown in Fig. 3 showing a modified way of applying the invention.

My invention is preferably formed of a single layer strip or plate 2 of bendable but relatively stiff material such as sheet metal or the like, and preferably of wedge-like shape as shown in Fig. 5 of the drawing. The upper edge of this strip or plate 2 is bent upon itself to form a flange 4. Two preferably horizontal slots 6 and 8 are provided in the front wall 9 of the carton or box 10. These slots are spaced from each other and are of such length as to conform to the wedge-like shape of the metal strip 2, the slot 6 thereof preferably being of greater length than slot 8.

After opening the carton 10 by inserting a knife or similar cutting tool under its lid or cover 12 and cutting or tearing along the edges 14 and 16 or by otherwise lifting the lid from the carton so that it hinges along its rear edge 18, the strip 2 is inserted in slots 6 and 8. Figs. 1 to 4 show my preferred way of applying the device by inserting the metal strip through slots 6 and 8 from the inside of the carton so that it rests against its inner wall while Fig. 8 shows my device inserted from the outside and resting against the outside of the front wall 9.

After inserting the strip 2 the lower part of the tapered portion 20 protruding from slot 8 is then bent upwardly so as to press against the bridge 22 which comprises the portion of the carton between the slots 6 and 8. The bent over tapered portion 20 thus exerts a clamping action on the bridge 22 securely fastening the device to the carton.

In order to close the carton or box 10, the flange 4 is pulled or pressed away from the lid or cover 12. The front wall 9 is thereby bent outwardly and the lid is then pressed into closed position. When the drag or pressure on flange 4 is released, the natural resiliency of the material of which the carton or box is made, will tend to straighten the front wall 9 to take its original shape. The flange 4 will thereby overlap the lid 12 and hold it in locked position.

The opening and closing of a carton to which my new device has been applied may, however, also be achieved in other ways. After opening the box for the first time and inserting the device, (if the same has not already been provided

by the manufacturer), the front wall 9 may for example be bent slightly outwardly. In order to open or close the carton, it will now only be necessary to grip and squeeze the two side walls of the 5 carton adjacent the front wall 9 in the vicinity of the top portion, to lift or to close the lid 12 and to release the pressure on the side walls.

My invention may be sold to the public individually as shown in Fig. 5, or it may be applied to 10 a carton during the manufacture thereof as shown for example in Fig. 4. In the first mentioned form the device may be enclosed in the wrapper of a carton or may be removably attached to it in any other way, and a scoring may 15 be provided in the front wall 9 at the places 6 and 8. The consumer can then remove the device from its enclosure, open the lid of the carton, cut slots into the front wall 9 at the places indicated by the scoring with a finger nail or with 20 a sharp corner of the closing device, and insert the device in the manner indicated in Fig. 3 or 8.

In the construction as shown in Fig. 4, the device is inserted in and fixed to a carton during the manufacture and before shipment thereof. This 25 figure shows a box or carton 10 containing goods 24 such as for example food products, said carton being in unopened condition as usually sold to the consumer. The reference numeral 26 represents a bag of wax or other paper for shielding 30 the material from atmospheric influences.

As also indicated in Fig. 4 it is often customary to cover such cartons with a wrapper of paper or other material 28 on which advertising matter 35 may be printed or through which advertising matter on the carton may be viewed. Fig. 4 shows this wrapper 28 as covering the portion 30 of the strip 2 thereby sealing the carton tightly at that point. However, the strip 2 obviously may 40 also be inserted after covering the box with the wrapper. After opening the carton 10 in the usual manner as already described, the strip 2 is bent backwardly into operative position so as to lie flat against the inside of the front wall 9 with its flange 4 now extending over the lid 12 as 45 shown in Fig. 3.

In the modification of the invention as shown in Fig. 8, the strip is applied to the outside of the carton. The wrapper 28 may either be placed on the carton 10 before inserting the strip 2 through 50 the slots 6 and 8, or the strip 2 may be inserted first and later covered by the wrapper 28. In applying this modification it is only necessary to bend the upper portion of the strip 2 away from the carton 10, to slit the box open along the edges 55 14 and 16, and to bend the strip 2 back into its original position.

The advantage of the modification of my new invention as shown in Fig. 8, aside from its main 60 purpose as described, resides in the fact that the strip may be inserted more easily into the carton and in that it serves to strengthen the closure of the lid 12 which is usually weakened by scoring along the edges 14 and 16 for facilitating the opening of the carton.

Any of the modifications of my invention permit 65 the hinged lid of a carton to be retained securely in position when the carton is not in use. The invention is of advantage when applied to cartons containing food products such as flour, cereal, sugar, and the like, and particularly when applied to cartons for such food 70 stuffs as are sold to housewives. Because of the invention accidental tipping or dropping of the carton will not result in a spilling of the material 75 from the carton and consequent loss of such

material. Moreover, the invention aids in protecting the material from atmospheric conditions and consequent spoiling.

As previously mentioned, the simplicity of the device renders its application an easy matter 5 when sold separately from the carton. With simple directions printed on the carton even a child can insert the device properly. The device may, however, also be inserted by the food product company before shipment of cartons containing 10 their products.

It will readily be seen from this specification and from the accompanying drawing that the device can be manufactured at a very low cost and can be applied to a carton in a very simple 15 manner.

It will also be understood that my new device may be constructed in any other form which performs the same mechanical functions as the device shown in the drawing and described in 20 the specification.

I claim:

1. In combination with a carton or box, means secured to one of the walls of said carton at the inside thereof for releasably retaining the lid 25 of said carton in closed position after the original closure of said carton has been opened, said means comprising a strip of bendable but relatively stiff material, a tongue portion at one end of said strip, said carton having slots in one of 30 its walls, said tongue portion passing through said slots and being bent upwardly upon itself so as to clamp the wall of said carton between said slots, and securing said strip to said wall, said strip being bent toward the inside of the 35 carton when said carton is in originally closed position, said lid when in opened position being hinged to said carton along one of its edges opposite said strip, a flange at the other end of said strip whereby said lid can be releasably secured to said carton after the original closure thereof has been opened and said strip has been bent so as to rest flatly against said wall. 40

2. In combination with a carton or box, means at the inside of said carton for releasably retaining the lid of said carton in closed position after the original closure of said carton has been opened, said means being secured to one of the walls of said carton and comprising a strip of 45 bendable but relatively stiff material and a flange on said strip for holding the lid in closed position.

3. In combination with a carton or box, means at the inside of said carton for releasably retaining the lid of said carton in closed position 55 after the original closure of said carton has been opened, said means being secured to one of the walls of said carton and comprising a strip of bendable but relatively stiff material, a flange on said strip at one end thereof for holding the 60 lid in closed position, said carton having slots in spaced relation one above the other in one of its walls, said strip passing through said slots, a tongue at the other end of said strip and protruding from the lower slot, said tongue being bent upon itself to clamp the portion of said wall between said slots so as to secure said strip in fixed position to said wall. 65

4. In combination with a carton or box, means for retaining the lid of said carton in closed 70 position, said means comprising a strip of bendable but relatively stiff material, said strip comprising a flat body portion, a flange at one end of said body portion and a tongue-like portion at the opposite end, said body portion being of 75

- wedge-like shape, said carton having slots in spaced relation one above the other in one of its walls, said strip passing through said slots, said slots being of such length as to conform to the 5 wedge-like shape of said strip, said tongue-like portion protruding from the lower slot and being bent upon itself so as to press against the wall of said carton and to retain said strip in fixed position in said slots, said flange when in operative position extending over the edge of said 10 lid adjacent said wall for securing said lid in closed position.
5. In combination with a carton or box, means secured to one of the walls of said carton at the 15 inside thereof for releasably retaining the lid of said carton in closed position after the original closure of said carton has been opened, said means comprising a strip of bendable but relatively stiff material, said strip comprising a body portion and 20 a flange at one end of said body portion for holding the lid in closed position, said body portion being of wedge-like shape, said carton having slots in spaced relation one above the other in one of its walls, said strip passing through said 25 slots, said slots being of such length as to conform to the wedge-like shape of said strip, a tongue at the other end of said strip and protruding from the lower slot, said tongue being bent upon itself to clamp the portion of said wall between 30 said slots and to secure said strip in fixed position to said wall.
6. In combination with a carton or box, means for retaining the lid of said carton in closed position, said means comprising a strip of bendable but relatively stiff material, a flange at one 35 end of said strip and a tongue at the other end; said flange being adapted to strengthen the original closure of said carton and to retain the lid of said carton releasably in a closed position after said original closure has been opened, said carton having horizontal slots in spaced relation 40 one above the other in one of its walls, the lower portion of said strip being of wedge-like shape and passing through said slots, said slots being of such size as to conform to the wedge-like shape of said lower portion, the upper portion of said strip resting against the outside of said wall, said flange extending over the edge of said lid adjacent said wall, said tongue protruding from the lower slot and being bent upwardly so as to press against the outside of said wall and to secure the strip in fixed position to said wall. 5
7. In combination with a carton or box, having a flexible wall and a hinged lid, means secured to said wall for releasably retaining the lid in closed position, said means comprising a strip of bendable but relatively stiff material and a 15 flange on said strip, said flange normally extending over the edge of said lid adjacent said wall and being adapted to be withdrawn from said lid by bending said wall transversely with respect to said lid. 20
8. In combination with a carton or box having a flexible wall and a hinged lid, means secured to said wall at the inside thereof for releasably retaining said lid in closed position after the original closure of said carton has been opened, 25 said means comprising a strip of bendable but relatively stiff material, a flange at one end of said strip and a tongue at the other end, said carton having slots in spaced relation one above the other in said wall, said strip being of wedge-like shape and passing through said slots, said 30 slots being of such a size as to conform to the wedge-like shape of said strip, said tongue protruding from the lower slot and being bent upwardly so as to press against said wall and to retain said strip in fixed position in said slots, said flange normally extending over the edge of said lid adjacent said wall and being adapted to be withdrawn from said lid by bending said wall transversely with respect to said lid for opening 35 or closing the same. 40

GEORGINA F. JONITZ.
